ELECTRIC SWITCH

Jakob Kruithof, Louis Jacques Ghislain Nys, and Jules Louis Joseph Donceel, Antwerp, Belgium, assignors to International Standard Electric Corporation, New York, N. Y., a corporation of Delaware

Application April 3, 1952, Serial No. 280,252

Claims priority, application Netherlands April 13, 1951

10 Claims. (Cl. 179—27.54)

The invention relates to an electric switch, e. g. for use in telephone systems, and more particularly to a switch of the type disclosed in the Belgian Patent No. 488,634 (J. Kruithof 40) which is essentially a multi-switch, i. e. a switch with a plurality of inlets and a plurality of outlets with means for the interconnection of any one inlet with any one outlet.

The switch disclosed in that patent included two main parts: the contact bank and the operating mechanisms for establishing a connection between an inlet and an outlet. The contact bank formed a three-dimensional lattice of spaced crossing points between conductors respectively belonging to a first and to a second set. Parallel rows of such crossing points could then be bridged by means of contact fingers and the operation of these contact fingers was controlled by means of a crossbar arrangement, i. e. a set of clutch or select bars and another set of hold or actuating bars permitting to select a particular contact finger by using a number of electro-magnets controlling these bars which is appreciably smaller than the total number of fingers.

The object of the invention is to improve the type of switch described above, one particular object being a reduction in the number of select or clutch bars which are necessary for a switch having a predetermined number of outlets.

A feature of the invention resides in an electric switch with a plurality of inlets and a plurality of outlets and comprising a first set of fixed parallel conductors, i. e. outlet conductors, a second set of parallel conductors substantially perpendicular to those of the first set and interleaved therewith so as to form a three-dimensional lattice of spaced crossing points, parallel rows of which, extending in a direction substantially perpendicular to both sets of conductors, can be bridged by means of outlet contact fingers, one for each row and movable substantially perpendicular to both the first and the second sets of conductors, while furthermore said conductors of the second set are used as intermediate conductors between conductors of the first set, i. e. outlet conductors, and fixed conductors of a third set of conductors, i. e. inlet conductors, whereby each connection between an inlet and an outlet is established via one or more intermediate conductors in series.

The above mentioned and other objects and features of the invention will become more apparent and the invention itself will be best understood by referring to the following description of embodiments taken in conjunction with the accompanying drawings which represent:

Fig. 1, a block diagram of a multi-switch;

Fig. 2, a schematic representation of a multi-switch showing the various contacts;

Fig. 3, a schematic representation of a modified multi-switch showing the various contacts;

Fig. 4, a schematic representation of the mechanical parts necessary for the operation of a multi-switch as shown in Fig. 3;

2

Fig. 5, a schematic representation of a partial modification for the switch shown in Fig. 4;

Fig. 6, a schematic representation of an embodiment of a multi-switch in accordance with the invention;

5 Fig. 7, a schematic representation of the mechanical parts necessary for the operation of a multi-switch as shown in Fig. 6;

Fig. 8, a perspective view of part of the multi-switch schematically shown in Figs. 6 and 7;

10 Fig. 9, a perspective view of another part of the multi-switch schematically shown in Figs. 6 and 7;

Fig. 10, a perspective view of yet another part of the multi-switch schematically shown in Figs. 6 and 7;

15 Fig. 11, the manner in which Figs. 8, 9 and 10 should be assembled.

Referring to Fig. 1, the latter shows the general principle of a multi-switch M with m inlets and n outlets. Each of these inlets and outlets may, of course, include any number of conductors, i. e. p , which are used for each connection from any one inlet to any of the outlets.

20 Referring to Fig. 2, the latter shows a schematic arrangement for the electrical contacts which are needed for the various connections in the multi-switch M, these contacts being numbered in accordance with the particular connection which the contact can effect, e. g. contact ij provides for the connection of the i th inlet to the j th outlet. For Fig. 2 and also in Figs. 3 and 6, it should be noted that the fact several conductors may be needed for each connection, is disregarded in order not to complicate the figures.

25 Referring to Fig. 3, this represents a modification of Fig. 2, in which two-way contacts are used, i. e. contact $11-2$ provides for the connection between the first inlet and either the first or the second outlet, in accordance with the sense of displacement of the contact. The principle of such an arrangement is also well known and has, for example, been disclosed in the Belgian Patent Number 501,688 (G. X. Lens 44).

30 Referring to Fig. 4, the latter is a known arrangement representing schematically the necessary mechanical parts for operating the contacts included in the multi-switch M schematically shown in Fig. 3.

35 The Belgian Patent Number 477,334 (G. X. Lens 37) discloses a contact bank with a plurality of horizontal conductors interleaved with a plurality of vertical conductors so as to form a three-dimensional lattice of spaced crossing points between conductors of the first set and conductors of the second set, i. e. between inlet conductors and outlet conductors. The latter can generally be assumed to be fixed conductors, while the former are resilient or at least portions of these are resilient so as to permit the necessary displacement to establish contact with a corresponding outlet conductor.

40 Alternatively, these horizontal conductors can be provided with suitable contact extensions and therefore only these need be resilient so that they may be displaced to effect contact with an outlet conductor. As disclosed, for example, in Belgian Patent Number 501,688 (G. X. Lens 44), contact fingers are used to displace the contact extensions provided on the horizontal conductors, in order to establish the connection. These contact fingers as disclosed in said Belgian patent, are located at right angles to both the horizontal and the vertical

45 conductors and they will generally be used to drive a whole row of contacts by displacing the fingers longitudinally in one or the opposite sense. Accordingly, by referring to Fig. 3, these contact fingers, although they are not shown in that figure, can be assumed to be located substantially at right angles to both the inlet and the outlet conductors.

50 These fingers are, however, schematically represented

in Fig. 4, e. g. F_{11-2} will be used to drive a plurality of contacts $11-2$, only one of which is shown in Fig. 3 although, in general, there will be a number p of such contacts in accordance with the number of conductors which are used for each connection between any inlet and any outlet.

Fig. 4 is more particularly related to the mechanism necessary for the operation of the fingers such as F_{11-2} and shows selective means for selecting a vertical row of fingers, these selective means comprising a vertical or select bar corresponding to each vertical row of fingers, e. g. vertical bar V_{1-2} for the fingers such as F_{11-2} . Only the first two (V_{1-2} , V_{3-4}) and the last (V_{n-1-n}) vertical bars have been shown but it is evident that the number of vertical bars is immaterial and depends on the capacity of the switch. The selection of a vertical row of fingers is essentially a clutch operation since the fingers will not be actually displaced. As soon as this selection is performed, actuating and holding means will be used to cause the displacement of a particular selected finger. This has also been schematically represented in Fig. 4 by horizontal or hold bars of which only the first two (H_1 , H_2) and the last (H_m) have been shown.

Therefore, referring to Figs. 3 and 4, and assuming a connection is desired between inlet No. 1 and outlet No. 1, the contacts such as $11-2$ and accordingly the finger F_{11-2} should be operated. The vertical select bar V_{1-2} will thus be first displaced, whereafter the displacement of the horizontal hold bar H_1 will provoke the displacement of the finger F_{11-2} which is located at the cross point of the bars V_{1-2} and H_1 . Various means can be used to cause the displacement of the select bars and the hold bars but Fig. 4 shows in a schematic manner that servo mechanisms are used to cause the displacement of both types of bars. An electromagnet such as VM_{1-2} is first of all used to select a vertical bar, i. e. V_{1-2} , and as soon as this selection is performed, a common bar H will be displaced under the control of the servo-magnet VS , the latter displacement causing the movement of the selected vertical bar, i. e. V_{1-2} .

A servo-magnet can also be used to control the movements of the horizontal bars and although each horizontal bar such as H_1 , will first of all be selected by the operation of a corresponding electro-magnet, i. e. HM_1 , the actual operation will be performed under the control of the common bars VL and VR which are controlled by the servo-magnets HSL and HSR . The use of two common bars and two servo-magnets is here necessitated in view of the fact that it is desirable to displace the horizontal bars such as H_1 in two opposite senses resulting in the displacement of the corresponding fingers, i. e. F_{11-2} , also in two opposite senses. This is schematically indicated in Fig. 4 by the arrows f_1 , f'_1 for the horizontal bars and f_2 , f'_2 for the fingers. In this manner, depending upon the sense of displacement of the horizontal bar, e. g. H_1 , and assuming the vertical bar V_{1-2} has first of all been displaced, a connection can be established via the contacts $11-2$ either between inlet No. 1 and outlet No. 1, or between said inlet and outlet No. 2.

The use of a servo-magnet is particularly advantageous when the horizontal bars are movable in two opposite senses, since if this were avoided, two electro-magnets would have to be used for each horizontal bar resulting in the use of twice as many electro-magnets such as HM_1 . If the number of inlets and accordingly the number of horizontal bars is fairly considerable, the use of a servo-mechanism will certainly be advantageous in such a case.

Fig. 5 shows a partial modification of the controlling arrangement shown in Fig. 4 and represents a code bar mechanism CB , also called permutation bar mechanism, by means of which the number of electro-magnets such as VM_{1-2} is appreciably reduced, these magnets being replaced by a smaller number of so-called code bar magnets such as CM_1 , a plurality of which may be simultane-

ously energized in different combinations, resulting in the selection of a particular vertical bar such as V_{1-2} corresponding to a particular combination. Such code bar mechanisms generally operate on a binary basis, since electro-magnets are essentially two-condition devices and such a mechanism is for example disclosed in the Belgian Patent Number 493,326 (O. Bracke—G. X. Lens 24-46).

Fig. 6 shows a schematic representation of the electrical connections for a modified multi-switch M . Instead of establishing a direct contact between an inlet and an outlet, e. g. between inlet No. 1 and outlet No. 1 via contact $11-2$ when the latter is displaced towards the left, each inlet conductor is first directed to either one of two intermediate horizontal conductors, thereby affording an additional selection of one out of two. This principle will be exemplified by referring to a connection between inlet No. 1 and any one of the first four outlets, i. e. Nos. 1-4. Assuming it is desired to establish a connection between inlet No. 1 and outlet No. 3, contacts $1-b$ and $13-4$ will be closed, the latter towards the left, whereby the connection will be established via these contacts and the link (in dotted line) between terminals P_1 and P'_1 . The purpose of showing the link between terminals such as P_1 and P'_1 in dotted lines will be explained later but unless otherwise stated it can be assumed that there is a through connection between such terminals.

Referring to Fig. 7, the latter schematically shows the mechanical parts for operating a multi-switch as represented in Fig. 6. As in Fig. 4, only the first horizontal row of contact fingers has been partially represented but it should, of course, be understood that similar horizontal rows of fingers are provided for each inlet. These fingers are labelled in the same manner as those shown in Fig. 4, in order to show correspondence between the fingers and the contacts which they control. E. g. in Fig. 7, finger F_{11-4} is the finger controlling contacts such as $11-2$ and $13-4$. Two additional fingers per inlet have also been represented in Fig. 7, i. e. F_{1a} and F_{1b} and are respectively used to control the contacts such as $1a$, $2a$, . . . ma and $1b$, $2b$, . . . mb . Accordingly, referring to the example of a connection between inlet No. 1 and outlet No. 3, this will be achieved by displacing finger F_{1b} and also finger F_{11-4} . Whereas the sense of displacement, i. e. f_2 or f'_2 , is significant for the finger F_{11-4} , since in one case it will drive the contacts $11-2$ and $13-4$ to the left, and in the other case to the right, it will be observed from Fig. 6 that whether contacts such as $1b$ are displaced to the right or to the left, is totally immaterial. This can be readily understood from Fig. 7 which shows that the fingers such as F_{1a} and F_{1b} which will hereinafter be called intermediate contact fingers and the fingers such as F_{11-4} , F_{15-8} , . . . F_{1n-3-n} which will hereinafter be called outlet contact fingers, are all displaced under the control of the same horizontal bar i. e. H_1 . The latter therefore acts as common actuating means for both types of fingers. "Type" should be understood here as relevant to purpose rather than actual construction, since they might well be of similar design.

Since the horizontal bar such as H_1 can be displaced in two opposite senses, i. e. f_1 or f'_1 , thereby affording a selection of one out of two which is used to obtain a connection either to the odd numbered outlets or to the even numbered outlets, this selection of one out of two can only be used once and not again for the fingers such as F_{1a} and F_{1b} which should therefore establish the same electrical connection irrespective of the sense of displacement of the horizontal bar, as clearly indicated in Fig. 6.

The intermediate contact fingers such as F_{1a} are also selected in vertical rows by means of vertical select bars such as V_A in the same manner as for the outlet contact fingers. As shown in Fig. 7, a code bar mechanism CB is used to select a vertical bar such as V_{1-4} in accordance with the particular combination of code magnets CM_1 , CM_2 which are operated. The vertical bars V_A and V_B

are selected individually by means of electro-magnets VM_A and VM_B . As in Fig. 4, the actual displacement of the selected vertical bars is performed by means of the common bar H controlled by the servo-magnet VS . This common bar H need not necessarily control the displacement of the vertical bars V_A and V_B which can be displaced under the control of their individual magnet.

Also, although a code bar mechanism CB has been shown for controlling the selection of the vertical bars V_{1-4} , V_{5-8} , . . . V_{n-3-n} , it is evident that this could be replaced by individual electro-magnets for each vertical bar as in the case of the vertical bars V_A and V_B , in which case the common bar H and the associated servo-magnet VS can also be omitted. The selecting and operating mechanism for the horizontal bars will not be further described since it is identical to that already described in conjunction with Fig. 4.

The advantage of the type of construction disclosed in Figs. 6 and 7 resides in the fact that in this manner the number of vertical bars can be appreciably reduced as compared to the known arrangement shown in Figs. 3 and 4. Assuming that the multi-switch has a capacity of 100 outlets, and that the horizontal bars are movable in two opposite senses, the necessary number of vertical bars will be equal (in the known arrangement) to

$$\frac{100}{2} = 50$$

On the other hand, if intermediate conductors are used, e. g. between contact 1_a and contact $11-2$, the number of vertical bars will only be

$$\frac{100}{2 \times 2} = 25$$

i. e. V_{1-2} , V_{3-4} , . . . V_{49-50} , plus the two vertical bars V_A and V_B making a total of 27 vertical bars as compared to the original 100 and showing therefore a reduction of nearly 50%. This has also the advantage of reducing the largest dimension of the switch which is generally determined by the length of the common bar H and accordingly by the number of vertical bars in a row.

The actual size of the switch will not, however, be diminished since from that point of view the arrangement of Fig. 4 is the optimum one and since with the arrangements of Figs. 6 and 7 the reduction in length of the switch will be offset by the increase in depth, i. e. due to the fact that the fingers such as F_{11-4} will have to drive twice as many contacts, i. e. contacts $11-2$ and contacts $13-4$ instead of contacts $11-2$ (Fig. 3).

However, the increase in size will be determined by the ratio between the number of intermediate contact fingers and the number of outlet contact fingers which, in the example considered, is equal to $\frac{2}{5}$, producing a percentage increase of 8% with respect to the switch of optimum size shown in Fig. 4. Since this is very small it can obviously be disregarded as compared with the advantage of using a substantially reduced number of vertical bars and accordingly a substantially reduced number of contact fingers.

A constructional embodiment of the switch schematically represented in Figs. 6 and 7 will now be described.

This embodiment is shown in Figs. 8, 9 and 10 which should be assembled as indicated in Fig. 11 and which show a perspective view of a multi-switch. In its basic constructional aspect, the multi-switch is similar to that disclosed in the Belgian Patent Number 488,634 (J. Kruithof 40), in which to each inlet corresponds an individual switch, all the various individual switches being piled up on top of one another. Referring to Fig. 6, an individual switch such as that giving access from inlet No. 1, will therefore comprise the contacts 1_a , 1_b , $11-2$, $13-4$, $15-6$, $17-8$, etc. together with the necessary means for operating these contacts, it being understood that the total number of these contacts should, in fact, be multiplied by p , i. e. the number of conductors necessary for each connection between an inlet and an outlet.

To fix ideas, it will be assumed by way of example, that for the multi-switch shown in Figs. 8, 9 and 10, the number of inlets and correspondingly the number of individual switches is equal to 24, while the number of outlets is equal to 100, and the number of conductors for each connection is equal to 5. Referring more particularly to Figs. 8 and 9, which show the four corners of an individual switch, the latter will be assumed to correspond to inlet No. 8 to permit a systematic numbering of contacts in accordance with the scheme shown in Fig. 6.

The individual switch, e. g. that corresponding to inlet No. 8, is mounted on an insulated plate 1006 and essentially comprises a series of ten metal strips $81a$, $82a$, $83a$, $84a$, $85a$ and $81b$, $82b$, $83b$, $84b$, $25b$, strips $85a$, $81b$ and $82b$ only being shown. Each of these metal strips, e. g. $85a$ is provided with a number of oblique contact extensions which are designed to be driven into contact with vertical conductors such as 975 (the 5th conductor of outlet No. 97) or 985 (the 5th conductor of outlet No. 98) (Fig. 9). By referring to Fig. 6, it will therefore be appreciated that the metal strips such as $85a$ correspond with the so-called intermediate conductors which are shown in the latter figure, e. g. the conductor between contact 1_a and any of the contacts such as $11-2$, $15-6$ etc. for inlet No. 1.

The vertical conductors such as 975 and 985 correspond with the fixed outlet conductors which are shown in Fig. 6. All the oblique contact extensions carry contacting strips of precious metal such as $897-985$ which, in accordance with the lettering scheme used, refers to the contact permitting the connection of inlet No. 8 to either the fifth conductor of outlet No. 97, or the fifth conductor of outlet No. 98. Furthermore, at the end of each horizontal metal strip, there is also an oblique contact extension which is similar in design to the other contact extensions but which has the special purpose of connecting the metal strip to the inlet. For example, the horizontal strip $85a$ terminates into the oblique contact extension which carries the contacts $8a5$, which, when driven either in the direction of the arrow f_2 or f'_2 , will establish contact between the horizontal strip $85a$ and the inlet terminal P_{85b} which is connected to the fifth conductor of inlet No. 8. It will be readily seen that in Fig. 6, this corresponds (for the inlet) to contact 1_a effecting contact with terminal P_1 to which inlet No. 1 is connected, noting, of course, that the references such as 1_a and P_1 in Fig. 6 cover an arbitrary number of contacts or terminals, e. g. 5, in accordance with the number (p) of conductors necessary for such inlet-to-outlet connection.

Taking a particular example of the inlet-to-outlet connection, from inlet No. 8 to outlet No. 100, both the contact extensions carrying respectively, the contacts $8b1$ and $899-1001$ should be displaced, the first either in the sense of the arrow f_2 or in the sense of the arrow f'_2 , and the second in the sense of the arrow f_2 so as to establish an electric connection between the vertical conductor 1001 and the inlet terminal P'_{81b} via the horizontal metal strip $81b$. This is, of course, the required operation for one conductor only, i. e. the first and it should also be done simultaneously for the remaining conductors (2nd, 3rd, 4th and 5th) of the inlet-to-outlet connection (not shown).

These contact operations will be performed by means of the contact fingers such as F_{8b} , . . . $F_{897-100}$. To establish contact between the horizontal metal strip $81a$ and the vertical conductor 1001 , the finger $F_{897-100}$ will have to be displaced in the direction of the arrow f_2 whereby, by means of the slot 1007 , in the vertical part 1008 of the finger, the oblique contact extension carrying contacts $899-1001$ will be driven to establish contact with the fixed vertical conductor 1001 . To effect contact between the horizontal metal strip $81b$ and the inlet terminal P_{81b} , the finger F_{8b} which is similar in design to the finger such as $F_{897-100}$, will also have to be driven but the sense of the displacement, i. e. f_2 or f'_2 , is immaterial since the short vertical conductors 1009 and 1010 are

electrically connected together and to the terminal P_{81b} . This is, of course, not the case for the vertical conductors shown at the left-hand side of the switch (Fig. 9), which are the vertical multiple conductors, e. g. 991, and 1001 which extend through the whole height of the multi-switch through holes which have been made in the insulated plates such as 1006. In this manner, in accordance with the principles disclosed in the Belgian Patent Number 488,634 (J. Kruithof 40), all the conductors of each inlet can be connected to the vertical conductors corresponding to the various outlets.

Referring now to the manner in which the contact fingers such as F_{8b} (intermediate contact finger) and $F_{897-100}$ (outlet contact finger) are driven by a common horizontal bar corresponding to a particular inlet, i. e. H_8 (Fig. 7), the latter has been partially represented in Figs. 8 and 9 and is essentially a profiled bar provided with slots such as 1011, each slot corresponding to a particular finger such as $F_{897-100}$. The front end 1012 of this finger which is displaced in the direction of its length, i. e. arrows f_2 or f'_2 , is also provided with a slot 1013 in which the end 1014 or a part integral with the fork-shaped member 1015 is engaged, this fork-shaped member 1015 being mechanically coupled, in a horizontal plane only, with the lever 1016 which is allowed to pivot in a vertical plane and more particularly in the sense of the arrow f_3 inside the forked end 1017 of the member 1015 under the control of a helicoidal spring 1018.

Accordingly, when the lever 1016 has been moved downwards by some operating means which will be described later, it will be engaged in the slot 1011 whereby, upon the horizontal bar H_8 being displaced either in the sense of the arrow f_1 or in the sense of the arrow f'_1 , the lever 1016 will be driven in that sense and will, therefore, drive the fork-shaped member 1015 which will pivot in a horizontal plane around the pivot 1019, which, incidentally, also carries the spring 1018. Due to this displacement and assuming the horizontal bar H_8 has been driven in the sense of the arrow f_1 , the part 1014 mechanically coupled with the member 1015 will drive the contact finger $F_{897-100}$ in the sense of the arrow f_2 , whereby contact will be established between the horizontal metal strip 81a (intermediate conductor) and the vertical conductor 1001. Simultaneously, of course, contacts will be established between the horizontal metal strips 82b to 85b, and the vertical conductors 1002 to 1005.

By referring to Fig. 8, it will be observed that the manner in which the intermediate fingers such as F_{8b} are driven, is identical to the above described manner and accordingly, when the horizontal bar H_8 is longitudinally displaced in the sense of the arrow f_1 , and provided the lever 1020 has been previously displaced downwards in the sense of the arrow f_3 , the finger F_{8b} will be displaced in the sense of the arrow f_2 whereby contacts will be established between the horizontal metal strip 81b and the inlet terminal P_{81b} as well as between the horizontal metal strips 82b-85b and the inlet terminals P_{85b} to P_{85b} (not shown).

Referring now to the manner in which the levers 1016 and 1020 are displaced downwards, this is achieved by means of the vertical bars such as those schematically shown in Fig. 7, i. e. the intermediate vertical bars V_A , V_B and the outlet vertical bars V_{1-4} , V_{5-8} , etc. Since all these vertical bars are identical in construction and since they all operate in the same manner, only one vertical bar V_A has been represented in Figs. 8 and 10. Each vertical bar V_A consists of a U-shaped profiled bar which is guided in a fixed plate 1021 (Fig. 10) at its bottom and also through an aperture such as 1022 (for bar V_B which is not shown) in the fixed part 1023 at its upper end, the top end of the bar V_A having, of course, a cross section compatible with the shape of the aperture 1021.

Parts of the middle side of the U-shaped profiled bar V_A have been cut away so as to leave bridge-shaped parts

such as 1024 around which resilient strips such as 1025 are fixed, secure fixing being obtained by the projection 1026, these resilient parts being used to push the levers such as 1016 in a downward direction to place them under the control of their corresponding horizontal bar. It will be observed that the resilient part 1025 is T-shaped so that the top part of the T, 1027, is used to prevent undue upward displacement of the lever during the displacement of the horizontal bar.

It should be understood, that the necessary downward displacement of the vertical bar such as V_A is obtained under the control of an electro-magnet, i. e. VM_A (Fig. 7) which can be mechanically or otherwise associated with the vertical bar V_A . After the horizontal bar H_8 has driven the levers, e. g. 1016 and 1020, the corresponding vertical bar V_B (not shown) can now be restored to its original position, the association between the horizontal bar H_8 and the levers 1016, 1020 being maintained under frictional pressure as will be explained later. The restoring of the vertical bar to its original position will be carried out by means of the spring 1028.

Also by referring to Figs. 8 and 9, it will be observed that a centering mechanism has been provided for all the fingers such as $F_{897-100}$ (Fig. 9), this mechanism mainly comprising a spring 1029 which is respectively anchored around the small levers 1030 and 1031. These levers are respectively pivoted at one of their ends in apertures 1031 and 1033 respectively provided in a fixed part 1034. The other ends of these levers, i. e. 1035 and 1036 are therefore normally abutting against the vertical sides of the fixed part 1034 but project sufficiently beyond the vertical part 1008 of the finger $F_{897-100}$ so that when the latter is displaced either in the sense of the arrow f_2 , or in the sense of the arrow f'_2 , the displacement of the finger will be sufficient to either displace the end 1036 of the small lever 1031 or the end 1035 of the small lever 1030, whereby energy will be stored in the spring 1029 which will be used to restore the finger to a well defined rest position, the slot 1037 being provided to allow the displacement of the finger in the sense of the arrow f_2 without causing the latter to be blocked against the small lever 1030.

It remains now to explain how the vertical bars, i. e. V_B and $V_{897-100}$, were displaced downwards so as to permit a connection between e. g. inlet No. 8 and e. g. outlet No. 100. This will be done with reference to vertical bar V_{21-24} shown in Fig. 10, which is the sixth bar of a series of twenty-five outlet vertical bars. The bottom end of the vertical bar V_{21-24} has an associated lever mechanism 1038 which can pivot with respect to the vertical bar at 1039. The horizontal part 1040 of the lever 1038 normally abuts against an extension 1041 which is provided on the common horizontal bar H (Fig. 7). The remaining part 1042 of the arm 1040 is located above a set of code bars CB_1 , CB_2 , CB_3 , CB_4 and CB_5 . These code bars are the essential part of the code bar mechanism CB schematically represented in Fig. 7 and are each provided with slots in such a manner that when a particular combination of code bars is displaced in the direction of the arrow f_1 , slots will be aligned at one particular position along the length of said code bars whereby a lever arm such as 1042 will be able to drop in these slots. For the particular vertical bar considered, i. e. V_{21-24} , when the code bars CB_2 and CB_3 are displaced in the direction of the arrow f_1 , while the remaining code bars CB_1 , CB_4 and CB_5 remain in their rest position (as shown), the lever arm 1042 will be free to drop in the slots 1043, 1044, 1045, 1046 and 1047 assuming, of course, that the downward movement of the lever arm 1042 is no longer prevented by the extension 1041. The means for displacing the code bars have not been shown since any suitable means can be used, so that each code bar is operated by its respective code bar magnet, e. g. CM_2 (Fig. 7) for code bar CB_2 (Fig. 10).

Accordingly, once the vertical bar V_{21-24} has been selected by the energization of the code bar magnets CM_2 and CM_3 , the slots **1043**, **1044**, **1045**, **1046** and **1047** will be aligned, and by displacing the common horizontal bar H in the sense of the arrow f_3 , the lever arrangement **1038** will pivot in an anti-clockwise direction, the lever arm **1042** falling inside the various slots while at the same time, the other arm **1048**, which is provided with a hook **1049**, will also pivot in an anti-clockwise direction so that the part **1050** of the common bar H will cooperate with the hook **1049**, whereby, during the further downward displacement of the common bar H , the hook **1049** will be driven downwards and accordingly will drive the vertical bar V_{21-24} in the direction of the arrow f_3 . For the connection which has been considered above as an example, it is, of course, the vertical bar V_{97-100} which will have to be displaced downwards and this may occur by the displacement of the code bars CB_5 , CB_4 and CB_1 . The code bar guide rods **1051** and **1052** which have been shown in Fig. 10, are provided with spacers such as **1053** to maintain the proper spacing between the various code bars.

It has been mentioned above that any operated finger is maintained in its actuated position by frictional pressure between e. g. the horizontal bar H_3 and the lever **1016**. This frictional pressure is quite sufficient to ensure a safe operation, since pressure is exerted not only by the centering spring **1029** but also by the back pressure on all the ten contact extensions such as **899-1001**.

Referring to Fig. 6, and more particularly to the connection between terminals P_1 and P'_1 shown in dotted lines, it will be readily appreciated that if this connection is omitted, the multi-switch can now provide ten conductors for each inlet-to-outlet connection instead of five with, of course, a corresponding diminution in the number of outlets, which becomes fifty instead of one hundred. Of course, if the multi-switch is to be used with ten conductors for each connection, the two intermediate contact fingers should always be in an actuated position, or else, their corresponding contacts should be by-passed to the inlet conductors.

It should be noted that although the embodiment of the multi-switch shown in Figs. 8 to 10 shows a code bar mechanism for selecting a particular vertical bar, this is by no means essential and individual electro-magnets could also be used to control each vertical bar. Also, the use of servo-mechanisms such as the horizontal bar H and the vertical bars VL and VR (Fig. 7), are not essential and may be omitted.

Further, the invention is neither restricted to a switch of any particular capacity nor to a switch in which only two intermediate vertical bars are used. For example, considering a multi-switch with 100 outlets, four intermediate vertical bars could be used whereby the number of ordinary bars would be reduced to thirteen (producing in fact a switch having a capacity of $13 \times 4 \times 2 = 104$ outlets), whereby the total number of vertical bars would be reduced to $13 + 4 = 17$, which is still less than the 27 vertical bars needed for the embodiment shown in Figs. 9-10. However, with such an arrangement, each finger now controls 4×5 contacts, i. e. 20 contacts instead of 10, and this may become a limiting factor. The real disadvantage, however, will be the increase in the size of the switch as compared to the optimum size and therefore the use of more than two intermediate vertical bars is probably only of advantage (for economic reasons) when the multi-switch has a larger number of outlets.

For example, in a multi-switch having 500 outlets, 4 intermediate vertical bars can be used whereby the number of outlet vertical bars is only 63, bringing the total number of vertical bars to $63 + 4 = 67$ instead of 250, which would be the required number if intermediate vertical bars are not used, and if each connection is established over a single contact only. In this case, the reduction in the number of vertical bars is striking and on the other hand, the in-

crease in size as compared to a 500 outlet multi-switch using 250 vertical bars, is negligible and is, in fact, equal to 7% only.

Further, the number of intermediate vertical bars such as V_A and V_B need not be restricted to an even number so that they can be operated on a binary basis. For example, in the case of a multi-switch with 500 outlets, 5 intermediate vertical bars could be used whereby the number of outlet vertical bars would be reduced to

10

$$\frac{500}{2 \times 5} = 50$$

bringing the total number of vertical bars down to $50 + 5 = 55$ and with an increase of size, as compared with the optimum, of only 10%.

While the principles of the invention have been described above in connection with specific apparatus, it is to be clearly understood that this description is made only by way of example and not as a limitation on the scope

20

of the invention.

We claim:

1. A clutch operating mechanism for an electric multi-switch comprising a plurality of spaced clutch members extending in a first plane, first actuating means for moving said members in a direction perpendicular to said first plane, a plurality of spaced actuating elements extending in a second plane perpendicular to said first plane for moving said clutch members into clutching relation with said first actuating means, second actuating means for moving said elements, a plurality of parallel movable code bars extending in a direction having a third plane, said third plane perpendicular to both said first and said second planes, a plurality of separate latch means, each pivotally connected to a different one of said elements, said latch means having a first portion and a second portion, said first portion extending transversely across said code bars and adapted to engage said bars under control of said second actuating means, said second portion adapted to be engaged by said second actuating means upon movement of said code bars to a predetermined position said first portion adapted to be pivoted against said code bars under control of said actuating means, and means connected with said second actuating means for restoring said latch means to disengage same both from said code bars and said second actuating means.

2. A clutch operating mechanism as claimed in claim 1 wherein each of said elements comprises a member having a plurality of spaced projecting strips extending perpendicularly therefrom, each strip associated with a different one of said clutch members and adapted to remain in movable engagement therewith.

3. A clutch operating mechanism as claimed in claim 2, wherein said strips have a T-shaped portion adapted to remain in engagement with said clutch members when said members have been moved by said first actuating means.

4. A clutch operating mechanism as claimed in claim 1, wherein the first portion of said latch means comprises a sensing arm adapted to engage said code bars and said second portion comprises a latch piece extending perpendicularly to said sensing arm.

5. A clutch operating mechanism as claimed in claim 1, wherein said latch means further comprises a cam surface adapted to cooperate with said restoring means.

6. A clutch operating mechanism as claimed in claim 1, further comprising a pair of spaced, fixed guide plates, each having a plurality of spaced slots therein, the slots in each plate in register with the corresponding slots in the other, each actuating element adapted to move through a corresponding pair of said slots.

7. An electric cross-bar multi-switch for use in a telecommunications system comprising a first set of spaced parallel conductors (e. g. outlet conductors) arranged in rows in two directions at right angles, a second set of parallel conductors substantially perpendicular to those

75

of said first set and interleaved therewith so as to form spaced crossing points, said second set of conductors comprising a first plurality of spaced movable contacts, first means for moving said contacts in either one of two directions substantially perpendicular to said first set of conductors to make electrical contact with either one of two of said first set of conductors according to the direction in which they are moved, a third set of conductors (e. g. inlet conductors), said second set of conductors comprising further movable contacts, additional means for moving said further contacts to make contact with either one of a pair of said third set of conductors, the conductors of each said third pair of conductors being electrically connected together and common actuating means for actuating both said first moving means and said additional moving means, whereby a circuit path from a given conductor of said third set to a given conductor of said first set, includes a given conductor of said second set via a first movable contact and a further movable contact associated therewith.

8. An electric switch as claimed in claim 7 wherein said first moving means comprises a plurality of parallel outlet contact fingers each adapted to move corresponding ones of said first movable contacts associated with conductors of said second set, said additional moving means comprising an intermediate contact finger mounted parallel to said plurality of outlet contact fingers and adapted to move corresponding ones of said further movable contacts associated with conductors of said second set, said common actuating means comprising a drive-bar, separate clutch means intermediate each of said contact fin-

5 gers and said drive-bar, said drive-bar adapted to move in a selected one of said outlet contact fingers and said intermediate contact finger simultaneously in the desired direction, whereby each connection between an inlet and an outlet is established through two electrical connections in series.

9. A switch as claimed in claim 8, wherein said clutch means comprises a clutch mechanism individual to each outlet contact finger and intermediate contact finger, a plurality of select bars each extending transversely of the clutch mechanisms associated with corresponding of said contact fingers, means for selecting a select bar, extending transversely of corresponding of said outlet contact fingers, means for selecting an additional select bar extending transversely of said intermediate contact fingers, common means for operating said select bars, said operated select bars adapted to couple said clutch mechanisms to said common drive-bar.

10 10. A switch as claimed in claim 9 and wherein said means for selecting a select-bar extending transverse of said outlet contact fingers comprises a code bar mechanism.
